(57) **CLAIM**

The ornamental design for a sofa for aircraft interiors, as shown and described.

DESCRIPTION

FIG. 1 is a top front perspective view of a sofa for aircraft interiors which embodies my new and original design therefore;

FIG. 2 front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines in FIGS. 1-2, 4 and 6 represent structure which is in the environment of the claimed design, but which does not form part of the claimed design.
